UNITED STATES PATENT OFFICE.

ALBERT ERICKSON, OF CHICAGO, ILLINOIS, ASSIGNOR TO SPLITDORF ELECTRICAL COMPANY, OF NEWARK, NEW JERSEY, A CORPORATION OF NEW JERSEY.

IGNITION DEVICE.

1,318,198.

Specification of Letters Patent.

Patented Oct. 7, 1919.

Application filed July 25, 1917. Serial No. 182,729.

To all whom it may concern:

- Be it known that I, ALBERT ERICKSON, a citizen of the United States, residing at 948 Addison street, Chicago, in the county of Cook and State of Illinois, have invented certain new and useful Improvements in Ignition Devices, of which the following is a specification, reference being had to the accompanying drawing.
- 10 The invention relates to new and useful improvements in ignition devices and more particularly to the operating mechanism for a generator operating to produce sparks in proper time for firing a gas engine.
- 15 An object of the invention is to provide means for driving the flux shifting member of the generator which includes a spring and devices carried by and movable with the flux shifting member which devices coöperate
- 20 with a fixed abutment for retarding the flux shifting member and compressing the spring whereby when said devices are released the spring may momentarily operate the flux shifting member for producing a spark.
- 25 A further object of the invention is to provide devices of the above character with means for rendering the same inoperative when the speed of the flux shifting member reaches a predetermined point.
- 30 These and other objects will in part be obvious and will in part be hereinafter more fully disclosed.

In the drawings, which show by way of illustration one embodiment of the invention,—

Figure 1 is a view showing a portion of a magneto or generator in side elevation and my improved driving mechanism therefor in vertical section;

40 Fig. 2 is a sectional view on the line 2—2 of Fig. 1;

Fig. 3 is a view similar to Fig. 2, but showing the retard device released so that the spring may drive the flux shifting

45 member;

Fig. 4 is a sectional view on the line 4—4 of Fig. 1 and showing the parts at the instant in which the retard device becomes effective and before the spring is compressed;

50 Fig. 5 is a similar view but showing the spring compressed and the retarding device just as it is released;

Fig. 6 is an end view of the driving device detached from the machine; and

55 Fig. 7 is a detail showing more or less

diagrammatically the make and break mechanism.

The invention consists broadly in an operating mechanism for a generator for producing current for sparks for gas engines. 60 The flux shifting member which may be of any desired type is normally rotated continuously for producing current. If, however, the flux shifting member drops below a predetermined speed through the slowing down 65 of the engine, the ignition current will drop from maximum decreasing the efficiency of the ignition.

The present invention is directed more particularly to a driving means for the flux 70 shifting member which operates said flux shifting member at a greater speed than the driving member therefor at the time of producing maximum ignition current for sparking purposes when the speed of the engine 75 is slowed down below a predetermined point and is not sufficient to produce said desired maximum current.

This driving mechanism includes a spring 80 which is located between the driving member and the flux shifting member and serves to communicate the movement of the driving member to the flux shifting member. carried by the flux shifting member is a device adapted to coöperate with a fixed 85 abutment for retarding the flux shifting member and compressing said spring. This device is released from the abutment after the spring is compressed to a certain point

by a cam movable with the driving member 90 and this spring operates for momentarily driving the flux shifting member so that it is operated at a greater speed than that of the driving member and in proper time for the spark for ignition. This device which re- 95 tards the flux shifting member is controlled by centrifugally operated members also mounted on and movable with the flux shifting member. These centrifugally controlled members are attached to the retarding device 100

and operate to hold the same out of engagement with the abutment when the speed of the armature or flux shifting member reaches a point so that the current generated is amply sufficient for producing efficient 105 ignition.

Referring more in detail to the drawings, I have shown the generator at G. Said generator may be of any of the usual high tension types including a primary and second- 110

ary coil. The flux shifting member is carried by the shaft 1 and may be either a wound armature or in the form of a flux shifting rotor.

5 The armature is operated by a driving member 2, which is secured to a coupling 3 on the end of the main driving shaft 4. This main driving shaft 4 is operated in proper timing with the main shaft of the 10 engine when the generator is used for producing ignition current. The driving member 2 is in the form of a sleeve fitting loosely within a driven member 5 which is keyed to the shaft 1 and held thereon by suitable 15 nuts 6. The driven member is formed with a sleeve 7 and freely mounted on this sleeve 7 is the sleeve 8 of the driving member 2. The driving member 2 is provided with a stud 9. The driven member is provided 20 with an inwardly projecting stud 10. Located between the studs 9 and 10 is a driving spring 11 on one side thereof and a buffer spring 12 on the other side thereof. The driving stud 9 operates the driven member 25 through the spring 11. This spring is of sufficient tension so that it will be under little or no compression during the normal rotation of the flux shifting member.

Carried by the driven member is a sliding 30 latch 13. This sliding latch is provided with diametrical projections 14 and 15, while the body portion of the latch is substantially of ring form and surrounds the sleeve 8 of the driving member. The inner 35 surface of the ring shaped body portion is provided with two cams 16 and 17 which are diametrically disposed relative to each other. The driving member 2 is provided with two projecting cams 18 and 19. The 40 projections 14 and 15 extend outwardly through slots in the driven member. The frame of the magneto G is formed with a shoulder 20. This shoulder is so disposed relative to the driven member as to be engaged by one of the projections 14 or 15 45 when said projection extends to its maximum distance beyond the outer surface of the driven member. The driven member is rotated in the direction of the arrow as indicated in Figs. 2 and 3. When the driving 50 stud is in the position shown in Fig. 4 and the spring 11 is free from compression, the cams 18 and 19 take the position shown in Fig. 2 relative to the cams 16 and 17. That 55 is, they are out of contact therewith. When in this position, the latch 13 will drop by gravity so one of the projecting ends thereof will engage the shoulder 20. This position of the parts is shown in Fig. 2 of the drawings. When the latch is in engagement with 60 the shoulder 20, then the driven member will be held from rotation and the driving stud will move to the position shown in Fig. 5, compressing the spring 11. During this 65 movement, however, of the driving member,

the cam 18 will be brought around into engagement with the cam 16 on the latch and will lift the latch so as to release the same from the shoulder. As soon as this latch is released then the spring 11, expanding will 70 force the flux shifting member forward at great speed and produce the proper maximum current for ignition purposes.

In Fig. 7 of the drawings, I have shown one form of make and break mechanism 75 which is operated by the armature shaft 1. Said make and break mechanism consists of a cam 21, a lever 22 having a contact point 23, and a fixed contact point 24. The lever 23 cooperates with the cam which 80 separates the contact points at proper time for ignition. This cam is timed so as to operate in proper timing with the releasing of the latch so that the maximum current is developed through the action of the spring 85 at the proper time relative to separating the contacts for producing the spark. It is understood, of course, that these contacts are in the circuit of the primary coil when the device is applied to a high tension magneto 90 or generator.

I have also provided means for rendering the retarding or stopping mechanism for the driven member inoperative when the armature shaft reaches the proper speed for 95 producing maximum current for ignition purposes. This means consists of pivoted levers 25 and 26. The lever 25 is pivoted at 27 to the sliding latch and the lever 26 is pivoted at 28 thereto. Each lever has 100 a projection 29 which serves as a fulcrum for the lever and the outer ends of the levers are slightly enlarged. These levers rotate with the armature shaft and when the speed of the armature shaft reaches a predetermined point the centrifugal force acting on the outer ends of the levers forces the same 105 outwardly, causing the fulcrum projections 29 to engage the inner wall of the driven member and this force on the outer ends of the levers brings the latch back to the position shown in Fig. 3, thus withdrawing the 110 latch from any possible contact with the shoulder 20.

The operation of my device will be apparent from the above description. In starting the engine when it is running at low speed, the levers 25 and 26 permit the latch to drop through its own weight so as to strike the shoulder 20. This retards the driven 115 member and the flux shifting member to which it is attached, permitting the driving member 2 to be compressed through the forward movement of the driving stud 9. At the proper time the cam carried by the 120 driving member will shift the latch so as to release it from the shoulder 20 and permit the spring to drive the flux shifting member at great speed, thus producing ignition current. The other end of the latch will then 125

become effective to stop the flux shifting member and automatically release the same so that for each rotation of the armature shaft it will be stopped or restarted twice. 5 This latch mechanism is especially designed for an ignition device wherein two sparks are produced for each rotation of the armature shaft. It will be understood, of course, that if any other number of sparks are produced, then the latch mechanism will be suitably modified so as to bring about a stopping and automatically releasing of the flux shifting member just at the proper time for producing the spark. As soon as the 10 speed of the driving member reaches a predetermined point then the levers come into action to render this retarding mechanism ineffective.

During the running of the engine, if for 20 any reason it is slowed down to a point where the generator would be inefficient, then the retarding or spring driving means for producing ignition current becomes effective.

It is obvious that minor changes in the 25 details of construction and the arrangement of parts may be made without departing from the spirit of the invention, as set forth in the appended claims.

Having thus described my invention, what 30 I claim as new and desire to secure by Letters Patent, is:—

1. An impulse device for an ignition generator comprising a driven member secured to the rotatable part of the generator, a driving member rotatably mounted on the driven member, a reciprocating latch carried by the driven member and having diametrically opposite projections adapted to alternately project beyond the periphery of the driven member when the latch is reciprocated to the end of its motion in that direction, means for engaging either of said projections to hold the driven member from rotation, a spring, means on said driven and driving members for setting said spring at tension by rotating the driving member in advance of the driven member, coöoperating means on the latch and driving member for moving the latch to release the driven member after the spring is set at tension and independently centrifugally operated arms acting on the latch to hold the same in neutral position after a predetermined speed of the rotatable part of the generator has been reached.

2. An impulse device for an ignition generator comprising a driven member secured to the rotatable part of the generator, a driving member rotatably mounted on the driven member, a reciprocating latch carried by the driven member and having diametrically opposite projections adapted to alternately project beyond the periphery of the driven member when the latch is reciprocated to the end of its motion in that di-

rection, means for engaging either of said projections to hold the driven member from rotation, a spring, means on said driven and driving members for setting said spring at tension by rotating the driving member in 70 advance of the driven member, coöoperating means on the latch and driving member for moving the latch to release the driven member after the spring is set at tension and independently centrifugally operated arms 75 pivoted on the latch but fulcrumed on the driven member for holding the latch in neutral position above a predetermined speed.

3. An ignition device comprising a generator having a rotatable flux shifting element, a driven member thereon and a driving member therefor, means for connecting the driving member to said driven member including an interposed spring, a double ended latch having cams thereon carried by 80 the driven member and slidable radially therein, a fixed abutment adapted to be engaged by both ends of the latch whereby the driven member is held from movement and the spring compressed, devices movable with 85 the driving member for engaging the cams on the latch to move the latch to a neutral position when the spring has been compressed to a predetermined degree whereby the 90 said spring may momentarily operate the driven member and centrifugally operated arms pivoted on the latch but fulcrumed on the driven member for holding the latch in neutral position at a predetermined speed of the driving and driven members. 95

4. An ignition device comprising a generator having a rotatable flux shifting element, a driven member thereon and a driving member therefor, means for connecting the driving member to said driven member including an interposed spring having 100 sufficient tension so that said driving and driven members normally turn together in the same timing, a double ended latch slidable radially of the driven member and rotating therewith, a fixed abutment adapted to be engaged by said latch twice per R. P. M. of the driven member whereby the driven member is held from movement and the spring compressed, devices movable with the 105 driving member for releasing the latch when the spring has been compressed to a predetermined degree whereby said spring may momentarily operate the driven member, and centrifugally controlled members pivotally 110 connected to said sliding latch for holding the same out of engagement with the abutment when the driven member is above a predetermined speed. 115

5. An ignition device comprising a generator having a driven member with a sleeve fixed thereto, a driving member having a sleeve fixed thereto, a spring interposed between the said driving member and the driven member and housed within said mem- 125 130

bers and being of sufficient tension so that the driven member and the driving member normally turn as one, a radially sliding latch mounted within said driven member and having a projection extending through an opening in the driven member, an abutment adapted to be engaged by the latch, cams carried by the sleeve of the driving member and adapted to engage the latch to move the same out of engagement with the abutment, weighted arms located within the driven member, said arms being pivoted to

the latch and having projecting fulcrums adapted to engage the side wall of the driven member whereby said arms will hold the latch out of engagement with the abutment when the driven member is moving above a predetermined speed. 15

In testimony whereof I hereunto affix my signature in the presence of two witnesses. 20
